Attest,

UNITED STATES PATENT OFFICE.

HEINRICH FISCHER, OF NURNBERG, GERMANY, ASSIGNOR TO THE FIRM: H. FISCHER & CO., OF NURNBERG, BAVARIA, GERMANY.

JUMPING-TOY FIGURE.

Application filed January 15, 1926, Serial No. 81,515, and in Germany November 19, 1925.

This invention relates to a jumping toy figure the jumping movements of which are produced by a slow advancing of the hind-legs which press by a projection onto the surface of a support and by a sudden jumping back of said hind-legs.

An embodiment of the invention is shown, by way of example, in the accompanying drawing in which:

10 Fig. 1 shows the jumping toy figure in horizontal section.

Fig. 2 is a vertical section, and

15 Fig. 3 is a similar vertical section, the toy figure being turned end to end with regard to Fig. 1 and the members of the same being shown in other position, as in Fig. 2.

The jumping toy figure is shown on the drawing as imitating a frog. It consists of the body 1 made in two parts and from sheet 20 iron, and of the front legs 2 made from sheet iron and rigidly fixed on the body. In the frog-shaped body 1 a clockwork 3 of commonly used type is located. A driving wheel 4 of the clockwork has outwardly directed catches 5 displaced at 90° the one to the other. These catches are adapted to act successively upon the hook-shaped top end 6 of an upright bow 7 which is oscillatably mounted on an axle 8 fixed in the clockwork 25 frame. A strong spiral spring 9, the front end of which is fixed on the frame of the clockwork casing 3 is attached with its other end to the upper ends of one side of the bow 7. In the lower end of the bow 7 a transverse rod 10 is journalled the ends of 30 which project through slots 11 in the frog-shaped body 1. On each projecting end of rod 10 a hind-leg 12 is fixed. The two hind-legs 12 are further connected the one with the other by a transverse rod 13 which is journalled in an upright bow 14, the upper end of which is fixed on a transverse axle 15 journalled in the frame of the clockwork casing 3. The bows 7 and 14 form together 35 a parallel guiding for the hind-legs of the frog, said hind legs having each a downwardly directed piece 16 fixed on its lower surface.

The operation of the toy-figure is as follows:

When the clockwork runs in the direction of the arrow *a* (Fig. 3) the catches 5 of the driving wheel 4 act successively upon the hook-shaped end 6 of the upright bow 7 and 40 make the same oscillate in a direction oppo-

site to that shown by arrow *b* (Fig. 3) so that the spiral spring 9 is put under tension. The rear legs 12 of the frog are therefore slowly pulled forwards under the body 1. As soon as the hook-shaped end 6 and 45 bow 7 is released by a catch 5 of the driving wheel 4 the hind-legs 12 have the tendency to jump back under the action of the spiral spring 9 but as the projecting pieces 16 of the hind legs 12 press against the support, 50 the legs cannot jump back and the body 1 will jump forward. When the next following catch 5 of the driving wheel 4 strikes against the hook-shaped end 6 of bow 7 the 55 operation begins again so that the toy-figure remains intermittently at rest during which time the hind legs 12 are pulled underneath the body 1 which jumps forward again.

It is not necessary that the toy-figure has the shape of a frog, it might imitate for instance another animal, a man, a vehicle or the like.

I claim:

1. A jumping toy-figure comprising in combination a body of convenient shape 60 imitating for instance a frog, a clockwork in said body, stationary front legs on the body, an axle journalled in the rear end of the clockwork, an upright bow pivotably mounted adjacent its upper end on said axle, a hook-shaped forwardly projecting end on said upright bow, means actuated by said clockwork for oscillating said bow including a strong spiral spring attached at the front end to the clockwork casing and at the rear 65 end to the upper end of said upright bow, a second axle journalled in said clockwork casing in front of said first mentioned axle, a downwardly projecting front bow fixed at the upper end on said axle, a transverse rod 70 journalled in the lower end of said spring-controlled upright bow and projecting at either end from said body, hind legs fixed one on each projecting end of said transverse rod, a transverse axle journalled in the lower end of said second mentioned upright bow and fixed in said hind legs, a downwardly and rearwardly projecting piece on the lower end of each hind leg to permit forward and to prevent rearward-movement of each leg relative to the supporting surface, whereby said body will jump forward when said spring-controlled bow is released.

2. A jumping toy-figure comprising in combination a body of convenient shape 75

imitating for instance a frog having a longitudinal slot at each side in the rear portion, a clockwork in said body, stationary front legs on the body, an axle journalled in the rear end of the clockwork, an upright bow pivotably mounted adjacent its upper end on said axle, a hook-shaped forwardly projecting end on said upright bow, a strong spiral spring attached at the front 10 end to the clockwork casing and at the rear end to the upper end of said upright bow, a driving gear wheel of said clockwork and four catches projecting from the outer surface of said driving gear wheel for intermittently moving said bow against the tension of said spring and then releasing it, 15 a second axle journalled in said clockwork casing in front of said first mentioned axle,

a downwardly projecting front bow fixed at the upper end on said axle, a transverse rod 20 journalled in the lower end of said spring-controlled upright bow and projecting at either end through said longitudinal slots of the body, hind legs fixed one on each projecting end of said transverse rod, a transverse axle journalled in the lower end of said second mentioned upright bow and fixed on said hind legs, a downwardly and rearwardly projecting piece on the lower end of each hind leg to permit forward and to prevent rearward movement of each leg relative to the supporting surface, whereby said body will jump forward when said spring-controlled bow is released.

In testimony whereof I affix my signature.
HEINRICH FISCHER.
